UNITED STATES PATENT OFFICE.

TORAKICHI UMEDA, OF TENNOJI-MURA, JAPAN.

ENVELOP-MACHINE.

Specification of Letters Patent. Patented Apr. 19, 1921.

1,375,618.

Application filed July 16, 1919. Serial No. 311,343.

To all whom it may concern:

Be it known that TORAKICHI UMEDA, a subject of the Emperor of Japan, residing at Tennoji-mura, Prefecture of Osaka, 5 Japan, has invented certain new and useful Improvements in Envelop-Machines, of which the following is a specification.

This invention relates to an apparatus for making seamless envelopes. The invention 10 more particularly relates to apparatuses of this character in which perforate patterns or molds, conforming to the shape of the product, are placed in liquid pulp contained in a vat, the bottom of which communicates 15 with a discharge pipe and carries a suction pipe extending to each mold, so that when the solution contained in the vat is withdrawn through the suction pipes and the discharge pipe, it is filtered through the 20 molds thus leaving a film or thin layer of the pulp on the outer surface of each mold. The invention is an improvement on this type of apparatus.

In the known apparatus, when the liquid 25 pulp is discharged through the mold, and the fiber of the pulp adheres to the mold, so as to inclose the latter, a vacuum is produced in the mold. If, owing to powerful suction, the vacuum produced is consider- 30 able, the layer of pulp deposited on the mold will be uneven, and a product of uniform thickness cannot be obtained. Furthermore, in such apparatus, a comparatively large force is required for lifting the 35 frame supporting the molds, which latter are attracted to the bottom plate.

The foregoing defects are eliminated by the apparatus according to the present invention, in which there is an air inlet pipe 40 for the purpose of introducing air into the mold, and, as a further improvement, an arrangement whereby the liquid pulp contained in the vat is free from disturbance, so as to allow the pulp fibers to adhere to 45 the mold. This latter arrangement consists of two or more horizontal partitions arranged in the lower portion of the vat and having perforations out of register with each other, and baffles by which the 50 speed of flow of the pulp caused by the suction, may be efficiently reduced.

In the accompanying drawings, an apparatus in accordance with this invention is illustrated in vertical section.

55 The liquid pulp is contained in a vat 1

through which extends an air inlet pipe 3 controlled by valves 2. This pipe has branches 5 one of which extends into each mold 4. The liquid pulp is introduced through a pipe 6 which has a regulating valve 7. 60 The suction pipes 11 are inserted in the bottom of the vat and beneath them is a discharge chamber 10 adapted to be emptied through the pipe 8 controlled by valve 9. The upper ends of the branch pipes 5 are 65 at a higher level than the upper ends of the suction pipes 11.

At the lower part of the vat there are horizontal partitions 12 in which are perforations out of register with each other. 70 Baffles 17 depend from the lower or lowest partition and extend upwardly from the bottom of the vat, in alternation with each other. Owing to these baffles the path of the liquid pulp passing into the vat is 75 lengthened and the speed of flow reduced. In the known apparatus referred to above, the liquid pulp is directly introduced at the bottom of the mold, so that the liquid pulp is agitated by the movement of the entering pulp and precipitation of the pulp fiber is prevented, while the fiber which may have adhered to the mold is washed off. Owing to this disturbance of the pulp the product 80 is damaged. This defect is eliminated in 85 the present apparatus by the partitions and baffles aforesaid. The construction of the new apparatus is very simple and its management is facilitated owing to the short length of the portion of the suction pipe 11 90 which enters the mold 4. In the known apparatus heretofore mentioned, this portion of the suction pipe is of a length substantially equal to the length of the mold, and the discharge chamber moves vertically with 95 all its accessories, so as to enable it to withdraw the liquid pulp through the mold while the latter is gradually descending. In the present apparatus a bottom cover 13 is provided at the lower end of each mold 4 100 and a carrier 15 is attached to the supporting frame 14 of the molds.

In the present apparatus, therefore, the purpose of the known apparatus is attained by fitting the lower ends 16 of molds 4 air-tight on bottom covers 13, which lie flat on the plate 12 and maintain the suction efficiency through the suction pipe. When the level of the pulp in the reservoir gradually descends to the upper ends of the suc- 110

tion pipes 11, during the operation of withdrawing the pulp into the discharge chamber 10 and through the discharge pipe 8, the pulp fibers adhere uniformly around the molds, so as to entirely cover the latter and a low pressure is produced therein. Should the suction through the pipes 11 become too strong and produce too high a vacuum within the molds the thickness of fiber deposited around the molds will not be uniform, and in consequence defective articles are obtained. Furthermore, a comparatively large force will be required to lift the frame that supports the molds since the bottom covers of the molds will be drawn by the vacuum against the partition 12.

It is to eliminate these defects, that the air inlet pipe 3 is provided. By opening this pipe, air is introduced into the interior 20 of the molds 4, so as to break the high vacuum produced therein; and although water enters into the branch pipe 5 during the suction of the pulp through the suction pipe 11, such water is automatically expelled when the air 25 inlet pipe 3 is opened.

Having now particularly described and ascertained the nature of this said invention and in what manner the same is to be performed, I declare that what I claim is:—
30 1. In an apparatus of the kind herein referred to for making seamless envelops, two or more horizontal partitions in the lower part of the vat, perforations out of register with each other in the said partitions, and 35 baffles in the path of the pulp admitted beneath the lower or lowest partition, for the purpose set forth.

2. In an apparatus of the kind herein referred to for making seamless envelops, a 40 suction pipe extending a short way into the mold, the bottom of the latter being closed air-tight and the said pipe being fixed in relationship to the mold, for the purpose set forth.

45 3. An apparatus for making seamless envelops comprising a vat, a supporting member arranged in said vat and carrying a plurality of perforate molds, pipes located in the vat and extending through the supporting device into said molds, said pipes being adapted to discharge water from said molds, and means for admitting air to the interior

of said molds when the vacuum within the molds has exceeded a certain degree.

4. An apparatus for making seamless envelops comprising a vat, pipes extending upwardly from the bottom of said vat and communicating with means for creating suction therein, a partition arranged within the vat and provided with plates which engage said pipes, perforate molds located in the vat and having their lower edges tightly engaging said plates, and means for admitting air into the interior of said molds.

5. An apparatus of the kind defined by 65 claim 4 in which the molds are provided with a supporting member, and a handle is secured to said supporting member to permit the molds to be simultaneously lifted from the vat.

70 6. An apparatus for making seamless envelops comprising a vat, a plurality of pipes extending upwardly from the bottom of the vat, means for creating suction within said pipes, stationary spaced partitions located within the vat and provided with unlined apertures, said pipes extending through said partitions and one of said partitions being provided with plates which engage said pipes, baffles arranged between one of said 75 partitions and the bottom of the vat for causing liquid pulp to travel by a circuitous path, means for admitting pulp to said vat, a plurality of perforate molds located within the vat and having their lower edges engaging said plates; an air pipe located in the vat and provided with branches opening into the interior of said molds, said branches having their upper ends at a greater height than the upper ends of said suction pipes, and means 80 for controlling the air fed through said air pipe.

85 7. An apparatus of the kind defined by claim 6 in which a supporting member is connected to the molds, and a handle is secured to the supporting member to permit the molds to be lifted from the vat.

90 In testimony that I claim the foregoing as my invention, I have signed my name in presence of two subscribing witnesses.
